DESIGN FOR A CARD INDEX CABINET

Harry S. Ray, New York, N. Y., assignor to Visible Index Corp., New York, N. Y., a corporation of New York

Application April 10, 1943, Serial No. 109,946

Term of patent 14 years

To all whom it may concern:

Be it known that I, Harry S. Ray, a citizen of Rumania and residing in New York city, in the county of New York and State of New York, have invented a new, original and ornamental Design for a Card Index Cabinet, of which the following is a specification, reference being had to the accompanying drawing, forming a part thereof.

cabinet, with the cover in closed position, showing my new design;

Figure 2 is a similar view showing the cover in open position.

I claim:

The ornamental design for a card index cabinet, as shown.

HARRY S. RAY.
